UNITED STATES PATENT OFFICE.

FRANK E. WAMPACH AND ARVID E. KARLBERG, OF CHICAGO, ILLINOIS.

TELEPHONE ATTACHMENT.

1,425,559.

Specification of Letters Patent. Patented Aug. 15, 1922.

Application filed December 22, 1921. Serial No. 524,062.

To all whom it may concern:

Be it known that we, FRANK E. WAMPACH and ARVID E. KARLBERG, both citizens of the United States, and residents of Chicago, in the county of Cook, State of Illinois, have invented certain new and useful Improvements in Telephone Attachments, of which the following is a specification.

Our invention relates to improvements in telephone attachments, particularly attachments in the form of a sub-base to be applied to the base of the ordinary desk telephone, and which sub-base is provided with a drawer containing a memorandum pad and

15 a pencil.

The object of our invention is to provide more simple and practical construction of the sub-base, particularly in connection with the support for the pencil, an important feature being the provision of a holder socket for the pencil which automatically swings up when the drawer is opened to bring the pencil in raised position so that it can be easily taken, and which will swing down to 25 lay the pencil against the bottom of the drawer when the drawer is closed.

The various features of our invention are clearly disclosed in the attachment shown on the accompanying drawing in which—

30 Fig. 1 is a plan elevation of the sub-base with the drawer pulled out,

Fig. 2 is a sectional view on plane 2—2, Fig. 1, and

35 Fig. 3 is a sectional view on plane 3—3, Fig. 1 with the drawer in.

The attachment base is circular and shallow and comprises the upper and lower walls 10 and 11 and the cylindrical wall 12, the diameter being substantially that of the base 40 of a desk telephone. Extending upwardly at the edge of the sub-base are a number of cleats or clamping tongues 13 for clampingly engaging with the base 6 of a desk telephone T as shown in Fig. 2.

45 The drawer structure comprises a flat bottom or supporting plate 14 and the outer wall 15, said wall being curved to the radius of the base and closing the opening 16 in the side wall of the base when the drawer is in 50 inner position. A knob 17 is provided on the wall 15 by means of which the drawer can readily be pulled out. In order to guide the drawer when being pulled out or pushed in to the base, sections 18 and 19 are de-

flected upwardly and inwardly from the bottom 11 of the base to form the guideways 20 and 21 for receiving the side edges of the drawer bottom. A stop tongue 22 is deflected upwardly from the bottom 11 against which the inner edge of the drawer bottom 55 abuts when the drawer is in closed position. Near the inner end of the drawer bottom a length of the metal is deflected upwardly to form a stop wall 23 which engages with the stop tongue 24 deflected downwardly from 60 the top 10 of the base, the outward movement of the drawer being thus stopped before the drawer is fully pulled out.

At one side of the drawer a section of the drawer is deflected upwardly to form the L 70 shape clamp 25 under which the memorandum pad 26 is inserted and held as clearly shown in Fig. 3, this pad being perforated along the plane 27 just in front of the bracket so that used sheets can readily be re- 75 moved therefrom.

Outside of the pad supporting bracket and near the inner end of the drawer bottom a leaf spring 28 is secured at its inner end and extends diagonally upwardly and outwardly and at its outer end supports a socket 29 which is of conical shape to receive the end of a lead pencil 30. The spring tends to raise the socket so that when the drawer is pulled out the socket will project 85 a distance beyond the edge of the wall 10 of the base and will be in inclined position so as to hold the pencil away from the bottom of the drawer in position to be conveniently grasped by the user. After use of the pencil 90 it is reinserted in the socket and then when the drawer is pushed in the socket will wipe against the top of the base and it will be forced down against the upper pressure of its supporting spring, and the pencil will be 95 swung down into position alongside the outside of the pad supporting bracket 25 as shown in Fig. 3. The socket not only holds the pencil in convenient position to be taken, but it also protects the point of the pencil 100 when the pencil is in place therein.

The construction of our attachment is very simple. It is made entirely of sheet metal and the various guides, stops and supports can readily be formed by deflecting sections 105 of the sheet metal. We do not desire to be limited to the exact construction and arrangement shown and described as changes

and modifications could readily be made which would still come within the scope of the invention.

We claim as follows:

- 5 1. An attachment for desk telephones in the form of a sub-base to be applied below the base of the telephone, a drawer for said attachment, a pencil supporting socket spring hinged on said drawer, said socket 10 being pressed down by the upper wall of said sub-base to hold the pencil inside of the drawer when the drawer is in, and said socket projecting a distance outside of said sub-base when the drawer is opened and 15 being then in inclined position to hold a supported pencil above the drawer bottom in a position to be readily taken.
2. An attachment for desk telephones in the form of a hollow sub-base, a drawer for 20 said sub-base, a memorandum pad in said drawer exposed when the drawer is opened, a pencil holder for supporting a pencil in said drawer, means tending to hold said pencil holder in position to support the 25 pencil above the drawer bottom where it may be readily grasped, and means operating to push said holder downwardly to hold the pencil inside of the drawer when the drawer is closed.
- 30 3. An attachment for desk telephones comprising a shallow cylindrical hollow base adapted to be secured against the underside of the telephone base, a drawer for said base, means on said drawer for supporting a memorandum pad, a pencil holder at one side of said pad for receiving the end of a pencil, a spring secured to the drawer bottom and secured at its other end to said holder, said spring tending to hold said holder in 35 inclined position to elevate the pencil above the drawer bottom, said holder being held down by the upper wall of said base when the drawer is closed to then hold the pencil against the drawer bottom.
- 40 45 4. An attachment for desk telephones consisting of a cylindrical shell metallic base having a drawer opening, a drawer slidable

into and out of said base through said opening, means for supporting a memorandum pad on said drawer, a spring secured at its inner end at the inner end of said drawer, a pencil holder secured to the outer end of said spring for supporting a pencil, said spring being free to raise said holder when the drawer is pulled out whereby to elevate said pencil so that it may be readily grasped, said holder being deflected downwardly against the force of said spring when the drawer is closed to thereby move the pencil down into position to permit closure of the drawer.

5. A detachable sub-base for supporting a desk telephone, a drawer for said sub-base, means for supporting a memorandum pad on said drawer, a pencil holder supported on said drawer, means for raising said pencil 65 holder when the drawer is opened, and means for forcing said holder downwardly when the drawer is closed to thereby move the pencil into the drawer so that the drawer may be closed.

6. An attachment for a desk telephone base consisting of a cylindrical shell having a drawer opening, a drawer slidable into and out of said shell through said opening, means for supporting a memorandum pad in said 75 drawer, a leaf spring secured at its inner end on the bottom of said drawer, a conical socket secured at its apex to the outer end of said spring, said socket serving for the reception of a pencil, said socket being inclined upwardly by said spring when the drawer is pulled out whereby a supported pencil is held in inclined position to be readily grasped, and said socket engaging against said base to be pushed downwardly 85 when the drawer is closed to then hold a pencil therein against the bottom of the drawer.

In witness whereof, we hereunto subscribe our names this 19th day of December, A. D. 90 1921.

FRANK E. WAMPACH.
ARVID E. KARLBERG.
